(57) **CLAIM**

The ornamental design for a basket, as shown and described.

DESCRIPTION

FIG. 1 is a perspective view of a first embodiment of a basket showing our new design;

FIG. 2 is a top view thereof;

FIG. 3 is a bottom view thereof;

FIG. 4 is front view thereof, the back view being identical;

FIG. 5 is a right side view thereof, the left side view being identical;

FIG. 6 is a perspective view of a second embodiment thereof;

FIG. 7 is a top view of FIG. 6;

FIG. 8 is a bottom view of FIG. 6;

FIG. 9 is a front view of FIG. 6, the back view being identical; and,

FIG. 10 is a right side view of FIG. 6, the left side view being identical.

The dash-dash-dash broken lines are included for purposes of illustrating portions of the basket and form no part of the claimed design.

1 Claim, 10 Drawing Sheets(56)
